UNITED STATES PATENT OFFICE.

JOHN B. WALKER, OF BIRMINGHAM, ALABAMA.

MOLDING APPARATUS FOR INGOT-MOLDS.

Specification of Letters Patent. Patented Aug. 24, 1915.

1,151,229.

Application filed February 27, 1915. Serial No. 10,988.

To all whom it may concern:

Be it known that I, JOHN B. WALKER, a citizen of the United States of America, residing at Birmingham, in the county of Jefferson and State of Alabama, have invented certain new and useful Improvements in Molding Apparatus for Ingot-Molds, of which the following is a specification.

My invention relates to improvements in apparatus for molding iron and steel ingot molds and molds for like hollow articles.

The main object of my invention is to provide an apparatus by means of which the manufacture of ingot molds may be materially cheapened and the number of operations so reduced that the molds can be produced rapidly and without skilled labor.

My molding apparatus is peculiarly adapted for use on a jarring machine but many of its advantages of construction will apply to the hand ramming of both core and cheek as is the present practice.

One object of my invention is to adapt both the core and cheek to be rammed at the same time on a jarring machine and to so design and assemble the parts that they will retain perfect alinement and not become loose when subjected to the jar and shock of the machine during the ramming operation and that they can be readily lifted apart by a crane and reassembled thereby into perfect alinement after the removal of the pattern.

By my invention I am enabled to draw away the core box and flask from the core and mold respectively with a single operation for each withdrawal, thus materially reducing the labor cost in the manufacture of ingot molds.

A further object of my invention is to make the core box and flask of such design and in so few parts that their maintenance is reduced to a minimum, their operation is simple, and much wear as compared with the present types of core boxes and flasks, being eliminated, their length of usefulness is materially extended.

A further novel feature of my invention relates to the stool which serves as a drag for the core and flask and is adapted to be removed from the jarring table so that the flask and core after being baked and prepared for molding can be assembled and poured on the same stool and drag on which they are rammed.

Other novel features of my invention re-

late to the construction of the flask in horizontally divided half sections which are so connected that they will separate when lifted apart; to the provision of gates in the flask section disposed opposite and below the position of the core molds for the ingot mold ears to give access into the flask to break the sand below the ears to facilitate the removal of the casting; and to the construction of a core box for use when the core is rammed separately from the flask and which is adapted to be centered on my combined stool and drag by the centering means for the flask.

My invention further comprises the novel details of construction and arrangement of parts which in their preferred embodiment only are hereinafter more particularly described and claimed, reference being had to the accompanying drawings which form a part of this specification, and in which:

Figure 1 is a vertical sectional elevation of the flask and core assembled on the stool drag for joint ramming, taken on the lines $y-y$ of Fig. 3. Fig. 2 is a side elevation of the same parts being lifted off the jarring table after the completion of the ramming operation. Fig. 3 is a partial horizontal sectional view taken on the line $x-x$ of Fig. 2. Fig. 4 shows the core box construction assembled on the stool drag for ramming the core separately from the cheek. Fig. 5 is a side elevation of Fig. 4 and illustrates the manner in which the core box is detached from the core by a single lifting operation. Figs. 6 and 7 show back and vertical sectional views of the removable flask gate.

Similar reference numerals refer to similar parts throughout the drawings.

On the jarring table 1 of any suitable jarring machine I seat a stool 2 having side openings provided therein to permit an elongated wedge key 3 to be inserted from side to side laterally therethrough and through a slot in the reduced lower end of the core plunger 4, which projects through a central opening in the top plate 5 of the stool, which plate forms the drag for the molding apparatus, being provided with a recess 6 in which is formed a sand mold that will protect the stool proper from the molten metal. This drag plate 5 is provided with a plurality of vent openings 7 under the core and is shaped in plan to conform substantially to the cross section of the flask

which is formed in two horizontal half sections 8. The marginal edge of the drag plate 5 at several points is notched at 9 and is provided with marginal dowel pin holes 10 on opposite sides. The lower flask section 8 is provided with a bottom flange 11 which carries vertical dowel pins 12 adapted to engage in the holes 10 and center and detachably hold the flask on the drag. Obviously the dowel pins may be carried by either member. The flask sections 8 at their meeting edges are provided with flanges 13 and one of these flanges, preferably the upper, carries vertical dowel pins 14 adapted to enter holes in the other flange and center the flask sections. Each flask section 8 is also provided with a pair of trunnions 15, the trunnions being preferably all arranged in the same vertical plane, and with a plurality of vent ports 16 to vent the cheek. The core plunger 4 is adapted to expand or contract a collapsible core 17, similar to that shown in my Letters Patent No. 997,027, and I lock the core plates in their expanded position by means of a top plate 18 and a wedge key 19 therefor driven through the plunger 4. The lower end of the plunger is drawn down by the wedge key 3 into rigid engagement with the stool drag 5.

The operation of the double process for ramming both cheek and core is as follows: The stool drag is seated on the jarring table, the core plunger 4 is passed down therethrough and keyed thereto, after which a pattern 21 is dropped about the core and upon the drag plate 5. A stripping plate 20 having marginal openings which register with the openings 10 in the drag plate 5 is then passed down over the mold and seated on drag plate 5. The lower flask member 8 is then lowered onto the stripping plate 20 with the dowel pins 12 entering openings 10 and centering it thereon with the flask, stripping plate and stool in alinement. The upper flask section is then picked up by the crane and lowered upon the lower flask section, the dowel pins 14 serving to center it thereon in reference both to the lower flask section and the stool. Thereafter the wedge key 3 is driven fully in to expand the core 17 and clamps 22 are then applied in the notches 9 in the drag plate to hold the stripping plate 20 to the lower flask 8, and clamps 23 are applied to fasten the flask to the drag plate and stool. The ramming operation then proceeds without it being necessary to rigidly connect the stool to the jarring table or to rigidly connect the flask sections 8 together. When the jarring operation is complete the crane is lowered and, by means of cable loops 24 suspended from its hook 25 and passed over the trunnions 15, the whole flask and stool are lifted off of the jarring table and conveyed to the drying pits where the clamps 23 are knocked loose and the crane lifts the flask with stripping plate 20 held thereto by clamps 22 with one operation from the mold and seats it over the gas burner. The mold is then removed and after the core and cheek have been baked and coated they are reassembled on the stool, the clamps 22 having been previously knocked loose to relieve the flask of the stripping plate. When thus assembled the apparatus is ready for pouring, and after pouring the flask sections 8 can be lifted away one at a time and cleaned before reassembling on the stool for the next operation.

In Figs. 4 and 5 I show my improved type of stool drag adapted for use in forming cores where it is desired to ram only the core, as for instance where the ingot molds are to be cast in chills or for any other reason it is desired to ram the flask separately from the core. Under these conditions I provide a core box formed of two similar half sections 26 which form vertical half sections of the box and are provided at their lower ends with wide base flanges 27 which are adapted to rest upon the drag plate 5. These flanges carry dowel pins 28 which engage in the dowel pin holes 10 in the drag plate 5. Along their vertical meeting edges the box sections are provided with flanges 29 and they are strengthened by horizontal reinforcing ribs 30. The flanges 29 are adapted to be permanently connected by bolts 31, it being my intention to so manipulate the box that it is not necessary to separate its sections in the core molding operation. Opposite the bolt holes for the bolts 31 the shoulders 29 are provided with rapping lugs 32 which form a circular boss adapted to be struck by the hammer or irons to clean the box. At its upper end each section 26 is provided with a perforated lug 33 through which a cable loop 34 is passed, and these loops are adapted to be passed over the crane hook when it is desired to raise the box after the ramming to strip the core, as seen in Fig. 5, the upwardly tapering character of the box and its vertical dowel pins permitting the box to be lifted off the drag without requiring the disconnection of any parts. By this arrangement the flask or chill will also have vertical dowel pins by which it can be lowered onto the drag plate 5 and brought into true alinement with the core by having its dowel pins engage in the same holes which received the dowel pin 28 of the core box.

The advantage of dividing the flask in half sections on a horizontal plate is that the sections can be readily assembled for vertical manipulation by the crane and they possess the full strength of an integral flask in resisting the expansive force of the sand under the ramming operation. Moreover, where the molds are rammed by hand, it

facilitates the operation to ram the lower half flask first and then set on the upper section and ram it.

A feature of my invention which is of especial advantage in connection with the molding of ingot molds and like devices having handles or ears is illustrated in Fig. 6, and consists in providing a flask section with an outwardly removable side gate or door 35 having on its inner face a curved flange or projection 36 disposed above and in position to prevent the sand from packing hard about a revoluble latch 37 having a handle 38 therefor which projects beyond the outer face of the gate. At its end opposite the latch the gate is provided with a lug or flange 39 adapted to engage the upper edge of the opening while the latch engages the lower edge and holds the gate firmly in position during the ramming operation. At the conclusion of this operation and after pouring the mold the gates are removed, and access is given through the door openings to the sand below the ear mold on the ingot mold. This sand can then be easily broken down and loosened so that the mold will free itself easily from the sand and the flask section can be lifted off from it without trouble. I may provide these door openings in all of the flask sections or only in those to be used opposite the lug or ear on the mold.

Having thus described my invention, what I claim as new and desire to secure by Letters Patent, is:

1. In combination, a jarring table, a stool supported drag resting on said table free of fixed connection thereto, a core detachably connected to said stool, a flask seated on the stool, means to center the flask relatively to the core, clamps to detachably connect the flask and stool, and a stripping plate detachably connected to the flask.

2. In an apparatus for molding ingot molds, a stool supported drag, a flask mounted on the drag, centering devices for drag and flask which permit them to freely disengage when parted vertically, a stripping plate, and means to detachably connect it to the flask for joint removal therewith from the drag.

3. In an apparatus for forming molds for ingot molds by the jarring process, a jarring table, a stool forming the drag mounted thereon free of fixed connection, a collapsible core having its arbor passing through the stool, wedge means to connect the arbor and stool, a stripping plate mounted on the stool, a flask mounted on the stripping plate, means to center both flask and stripping plate on said drag, and independent clamps to hold the parts together, one set of clamps connecting the flask and stripping plate, and the other set connecting the flask and stool drag.

4. In an apparatus for molding ingot molds, in combination, a drag, a flask, a stripping plate for the flask which is mounted on the drag, said stripping plate having its marginal edge interposed between and adjacent to the marginal edges of the drag and flask, clamp means to connect the flask and drag, and independent means to detachably connect the flask and stripping plate.

5. In an apparatus for molding ingot molds, a drag and a flask having bottom flanges, a stripping plate for the cheek having its marginal edges adjacent to the flask flange edges, a marginal flange on the drag which is provided with notches, and clamps to engage the flask and stripping plate opposite said notches, and other clamps to engage the flanges of the flask and drag.

6. In an apparatus for forming molds for ingot molds on a jarring machine, in combination, a combination stool and drag having a center hole and marginal dowel pin holes, a collapsible core comprising a vertically movable plunger having a shoulder near its lower end, which end is adapted to pass through said center hole in the drag, a wedge key to engage said plunger below the drag and draw its shoulder rigidly against said drag, laterally movable side plates for the core, means operable by the plunger to force said plates outwardly when it is drawn downwardly, a top plate to engage the upper ends of the core plates, a wedge engaging the plunger and top plate to force the latter against the core plates, a flask, clamps and dowel pins to connect the flask and drag, and means on both flask and core plunger for engagement with means to lift them vertically.

7. In an apparatus for forming molds for ingot molds, a stool and drag, a collapsible core, means to tie the core to the drag, a pattern surrounding the core and seated on the drag, a flask, a stripping plate connected to the flask and adapted to seat on the drag about the pattern, and means to lock the flask, stripping plate and pattern against lateral movement on the drag while leaving them free for vertical disengagement therefrom, substantially as described.

8. In an apparatus for molding ingot molds, a combination stool and drag for both core and cheek, a collapsible core, means to mount the core centrally of the drag, a core box for forming the core having a wide base flange, and centering means for the core box disposed at the margin of the drag, substantially as described.

9. In an apparatus for molding ingot molds, a core box having a wide base flange, a drag for forming both core and cheek, and vertically separable means to center and interlock the flange to said drag.

10. In an apparatus for molding ingot molds, a flask in two horizontal halves with

vertical guide pins, a drag and stool, a pattern in the drag, and vertical guide pins to center flask and drag, detachable clamps to hold flask and drag together after ramming 5 operation, and means on the flask for engagement with overhead lifting apparatus to strip flask and cheek vertically off the pattern after disengaging the clamps.

11. In an apparatus for molding ingot 10 molds, a core box divided into vertical half sections, means to permanently connect said sections, means for engagement with lifting apparatus whereby the core box can be moved vertically to strip the core, and rapping lugs provided at the engaging edges of 15 the box sections, substantially as described.
12. In an apparatus for molding ingot molds having cast ears thereon, a flask adapted to be raised to strip it from the 20 casing and having clean out side doors therein disposed in position to give access to

the sand under the ear on the mold when cast in the flask, and a door closure for said opening which can be opened from without to give access to the interior of the mold.

13. The combination with a flask adapted to be raised to strip it from the casting and having one or more clean out side openings therein, of door closures for the openings, said doors comprising latch means disposed on their inner faces and flange means which lock it in position on the flask, a flange to overhang the latch means and prevent the sand packing about and locking the latch, and an external means to throw the latches. 30 35

In testimony whereof I affix my signature in presence of two witnesses.

JOHN B. WALKER.
